Application April 7, 1952, Serial No. 280,936

3 Claims. (Cl. 302—52)

1

This invention relates to apparatus for storing and discharging pulverulent material, and particularly to mobile storage carriers and means associated therewith for discharging substantially-dry, finely-divided material from them.

The apparatus and method of the invention are especially designed for conveying and discharging large quantities of pulverulent materials, such as flour and other pulverulent food products, dry finely-divided chemicals, and other finely-divided materials, especially those which do not flow freely from ordinary storage receptacles.

It is well known that flour is particularly susceptible to infestation by insects if kept within a storage receptacle for any appreciable length of time. It is also well known that it is difficult to discharge flour from a large receptacle without expensive and complicated apparatus. Accordingly, it has been customary in the past to load flour from storage bins at the mills into large bags, and to transport the bags to the various places where the flour is to be used, which places are frequently at substantial distances from the mills. It is desirable to avoid the added operation of loading the flour into bags, because of the cost of the operation itself, the cost of the bags, and the danger of contamination of the flour during the loading procedure.

Apparatus has previously been designed to discharge flour from vehicles, but such apparatus has been objectionable because of wastage of the flour, failure of complete removal of the flour when it was discharged, or dusting by the material of the area around the vehicle during the discharge operation.

This invention provides an apparatus associated with a vehicle, such as a railroad car or a truck trailer, which is capable of discharging flour from such a vehicle at a minimum of expense and wastage of material, and which is self-cleaning so that all the flour may be discharged from the vehicle during a discharge operation without leaving any deposits in the vehicle where infestation may take place.

In transporting certain dry chemicals, it previously has been necessary that they first be stored in small containers before they could be shipped to the remote locations at which they were to be used, because of the deficiencies in known methods for transporting such chemicals in bulk, and particularly because of wastage of the chemicals and deposit of them in undesirable places. In some of the previous methods and apparatus designed for discharging expensive

2

chemicals, such as adipic acid, from a bulk receptacle, the wastage of the chemical during the discharge operation was so great as to make transporting in bulk expensive and inefficient. Moreover, when deposits of material were left in the receptacle after discharge, it was not possible to transport different chemicals in the same receptacle later because of contamination by the earlier-transported chemical. The apparatus and method of the present invention are designed to discharge pulverulent material, such as adipic acid, from a large mobile bin or container, such as a railroad car or a truck trailer, without permitting any appreciable wastage or contamination of the material and without permitting deposits of material to remain in the bin after the material is discharged therefrom.

The apparatus of the present invention comprises generally a mobile bin having walls defining an enclosed storage space, a substantially-vertical conveyor pipe suspended from the upper wall of the bin and extending down into the material contained in the bin, a curtain pipe surrounding the conveyor pipe and having an opening positioned above the level of material in the bin for admitting air from the storage space into the passage between the conveyor pipe and the curtain pipe, means for applying a suction pressure to the upper end of the conveyor pipe, and an opening through one of the walls of the bin for admitting air from the atmosphere into the bin. This apparatus permits air entering the bin through said opening to sweep over the material contained within the bin, to enter the passage between the conveyor pipe and the curtain pipe, and to pass downwardly through that passage across the surface of material below the conveyor pipe, to entrain such material and to pass upwardly through the conveyor pipe out of the bin, where the air-entrained material may be packaged or delivered to some convenient remote location.

The above apparatus in itself is capable of overcoming most of the disadvantages present with previously-proposed transportable-bin discharge apparatus. But a large amount of power is necessarily consumed in entraining the material stored in the bin in the air stream, so that the entrained material can be carried out of the bin. The lower end of the conveyor pipe is necessarily positioned quite close to the lower wall of the bin, so that all or substantially all of the material contained within the bin can be discharged. The weight of the material itself will cause the material below the lower end of the conveyor pipe to be formed

into a compact inert mass. To entrain such material, the air stream must have a high velocity, which necessitates that a large amount of power be delivered from the suction means.

It has been found that if the material within the bin is delivered in an aerated condition to a position directly below the conveyor pipe where it will be swept over by the air stream, the necessary velocity of the air, and consequently the power that must be supplied to the suction apparatus, is appreciably reduced. Accordingly, the present invention contemplates providing within the bin one or more gas-permeable members having their upper or material-conveying surfaces forming at least portions of the bottom wall of the bin, the gas-permeable members being inclined with respect to the horizontal, and having their lowermost ends positioned adjacent the lower end of the conveyor pipe. Each of the gas-permeable members has a plenum chamber extending along and below it into which a gas is forced so that the gas passes through the gas-permeable members and into the material supported thereby to aerate such material. The aerated material then flows downwardly along the upper surface of the gas-permeable members by gravity to a location below the lower end of the conveyor pipe where it can be picked up by the air stream from the curtain pipe.

The method and preferred embodiments of the apparatus of the present invention will be more fully described in conjunction with the accompanying drawings.

In the drawings:

Fig. 1 is a vertical sectional view taken on line 1—1 of Fig. 2 of a freight car embodying the present invention;

Fig. 2 is a horizontal sectional view on line 2—2 of Fig. 1;

Fig. 3 is a vertical sectional view taken on line 3—3 of Fig. 1;

Fig. 4 is a view of a portion of the apparatus shown in Fig. 3 drawn to a larger scale;

Fig. 5 is a vertical sectional view taken on line 5—5 of Fig. 6 of a truck trailer embodying the present invention;

Fig. 6 is a horizontal sectional view taken on line 6—6 of Fig. 5; and

Fig. 7 is a sectional view of a portion of the apparatus taken on line 7—7 of Fig. 5.

In Figs. 1 through 4, the invention is shown as embodied in a freight car 1 having an upper wall 2, end walls 3 and 3', side walls 4 and 4', and a bottom wall 5 defining an enclosed material-storage space 6. A pair of conveyor pipes 7 and 7' extend substantially vertically within the storage space 6 approximately equidistantly between the end walls 3 and 3'. The conveyor pipes 7 and 7' are spaced apart laterally, both from themselves and from the side walls 4 and 4'. The upper portions of the conveyor pipes 7 and 7' extend through the upper wall 2 and the roof 8 of the car into two of a number of access ports 9 and 9', respectively, which provide loading entrances to the storage space 6. The upper portions of the conveyor pipes are supported from the upper wall by clamps 10 and 10' attached to the upper wall. Clamps 10 and 10' have split rings 11 and 11' surrounding the conveyor pipes 7 and 7', respectively. The split rings are clamped about the pipes 7 and 7' by bolts 12 and 12', respectively, which connect the split ends of the rings. The bolts may be loosened to permit the conveyor pipes to be adjusted upwardly and downwardly to permit ad-

justment of the lower ends 13 and 13', respectively, of the conveyor pipes 7 and 7' with respect to the portion of the bottom wall 5 of the bin immediately beneath them. The lower ends of the conveyor pipes are spaced above the lowermost surfaces of the bottom wall 5 of the bin a distance determined by the type of material being conveyed and the desired rate of flow of the material.

Curtain pipes 14 and 14' surround the conveyor pipes 7 and 7', respectively, and are spaced therefrom by spacers 15 and 15', respectively, mounted on conveyor pipes 7 and 7'. The curtain pipes 14 and 14' are supported from the upper wall 2 by mounting plates 16 and 16' through which bolts 17 and 18, and 17' and 18', respectively, are threaded. The lower ends of bolts 17 and 18 and 17' and 18' are welded or otherwise fixed to the upper ends of the curtain pipes 14 and 14', respectively. The threaded bolts permit the curtain pipes to be adjusted vertically with respect to the upper wall of the bin, so that the positions of the lower ends of the curtain pipes may be varied with respect to the lower ends of the conveyor pipes 7 and 7'. It has been found that in most instances the most desirable position of the lower end of each of the curtain pipes with respect to the lower end of each of the associated conveyor pipes is such that the lower ends of the conveyor pipes lie in the same planes as the lower ends of the curtain pipes. However, the settings of the curtain pipes with respect to those of the conveyor pipes are determined by the type of material conveyed and may be different for different materials.

Suction discharge conduits for connecting the top of the conveyor pipes 7 and 7' to a remotely located storage bin or the like, and for applying suction to the conveyor pipes to cause discharge of the material therethrough, are indicated in dotted lines at 19 and 19'.

The freight car 1 has a pair of end walls 20 and 20' spaced inwardly from the end walls 3 and 3', respectively, of the bin to provide air spaces or chambers 20^a and 20^b, respectively, at each end of the car. Openings 21 and 21' in the end walls 3 and 3', respectively, allow air to pass into the air spaces or chambers 20^a and 20^b. A pair of filter units 22 and 22' are mounted opposite the openings 21 and 21', respectively, in said air spaces or chambers and remove foreign material from the air passing into the bin. The filter units also remove entrained material from any air which might pass out of the bin through the openings 21 at 21'.

The upper ends of the walls 20 and 20' terminate below the upper wall 2 of the car, and a baffle having laterally-extending surfaces 23 and 23', and longitudinally-extending surfaces 23^a and 23^b extends downwardly from the upper wall, the surfaces 23 and 23' being adjacent the walls 20 and 20', respectively, so that air admitted through the openings 21 and 21' must pass through filter units 22 and 22' and then flows upwardly and over the upper ends of walls 20 and 20' which then direct it downwardly against the upper surface of material in the bin.

In order to convey material from within the storage space 6 to positions beneath the conveyor pipes 7 and 7', four gas-permeable members 24 and 24' and 25 and 25' are provided. The laterally-spaced gas-permeable members 24 and 24' extend from the wall 20, and the laterally-spaced gas permeable members 25 and 25' ex-

tend from the wall 20', downwardly and terminate beneath the conveyor pipes 7 and 7' with their lowermost ends abutting.

Plenum chambers 26 and 26' and 27 and 27' extend along and below the gas-permeable members 24 and 24' and 25 and 25', respectively. Means for forcing gas under regulated pressure into the plenum chambers are indicated diagrammatically at 28 and 29. Such gas-forcing means may be a single apparatus and may be carried on the car or may be kept at discharge locations for connection to the plenum chambers when the car reaches the locations.

In order to direct material within the car onto the upper material-conveying surfaces of gas-permeable members 24 and 24' and 25 and 25', the bin is provided with flow-directing surfaces. These flow-directing surfaces comprise an inclined wall 30 extending between side wall 4 of the car and the adjacent sides of gas-permeable members 24 and 25, an inclined wall 30' extending between side wall 4' of the car and the adjacent side of gas-permeable members 24' and 25' and inclined walls 31 and 31' aligned to form an inverted V in cross-section, with their lower edges positioned at the adjacent longitudinal sides, respectively, of the gas-permeable members. All of the inclined walls 30 and 30' and 31 and 31' form angles with the horizontal such that material will flow along them by gravity onto the material-conveying surfaces of the gas-permeable members.

When the apparatus of Figs. 1 through 4 is to be used for discharging substantially dry pulverulent material from the freight car, gas under pressure is supplied to the plenum chambers 26 and 26' and 27 and 27' through means 28 and 29. The gas has a substantially uniform pressure throughout the length of the plenum chambers and passes from them through the gas-permeable members, thus aerating the material immediately overlying them. The aerated material flows downwardly by gravity along the upper surfaces of the gas-permeable members to positions beneath the lower ends of the conveyor pipes 7 and 7' and the curtain pipes 14 and 14'. The means 19 and 19' for supplying suction to the conveyor pipes 7 and 7', respectively, are then set into operation and air entering from the atmosphere through the openings 21 and 21' in the end walls of the freight car passes through the filter units 22 and 22' across the material in the bin to the curtain pipes 14 and 14'. Since the openings are located at substantial distances from the curtain pipes, the air must pass over most of the upper level of the material in the bin before it reaches the curtain pipes. Consequently, the air will sweep all dust formed above the level of material along with it, thus decreasing appreciably the possibility of a dust explosion in the car. The stream of air then passes up over the upper ends of the curtain pipes and downwardly through the passages between the curtain pipes and the conveyor pipes and across the material beneath the conveyor pipes and the curtain pipes. At these points the air entrains the aerated material and carries it upwardly through the conveyor pipes into the access ports 9 and 9', then through conduits 18 and 18' out of the bin and to the remotely-located storage bin from which it later is packaged or used.

The term "aeration" is employed herein to mean penetration of any gas, not necessarily air, into the material above the gas-permeable mem-

bers at sufficient speed to expand the material, and thereby reduce the particle-to-particle friction, but not at a speed sufficient to entrain particles of material in the gas stream.

When a pulverulent material is aerated by passage of a gas through a horizontal permeable member into it, it forms a definite angle with respect to the horizontal gas-permeable member. This angle is termed the angle of repose of the aerated material, and is substantially less than the angle of repose of the same material before aeration. If the gas-permeable member is inclined with respect to the horizontal at an angle at least as great as the angle of repose of the aerated material, aeration of the material will cause the material to flow by gravity along the conveying surface of the permeable member to the lowermost end thereof. The angle of repose of an aerated pulverulent material is dependent upon the characteristics of the particular material, and varies with different materials. However, it has been found that if the gas-permeable member has an inclination with respect to the horizontal of from about 4° to about 15°, practically any material which may be aerated will, when aerated, flow down such a member by gravity. Accordingly, the gas-permeable members 24 and 24' and 25 and 25' are preferably disposed such that their upper or material-conveying surfaces form an angle with respect to the horizontal at least as great as the angle of repose of the material in its aerated state.

It is not necessary that air be used to aerate the material. The gas fed into the plenum chambers 26 and 26' and 27 and 27' may be any gas which is inert with respect to the particular material in the storage space 6. The gas may be also heated or refrigerated, and, in some cases, it may be a gas which is chemically reactive with the material, depending upon the particular material and the characteristics which it is to have when discharged from the car. The gas-permeable members 24 and 24' and 25 and 25' are advantageously constructed of canvas, but may be of any gas-permeable material having a permeability not substantially greater than 5. The term "permeability" as herein employed is defined as the amount of air measured in cubic feed at 20° F. and 25% relative humidity which will pass through an area of one square foot of dry, porous stone in one minute when tested under an equivalent pressure differential of two inches of water.

It has been found that porous material having a permeability of from about 5 down to and including zero, as determined by the above definition, is satisfactory for use as the gas-permeable members in the apparatus of the present invention, and, accordingly, porous material having a permeability within that range is preferred for use with the present invention. In the case of some gas-permeable materials, the application of an air pressure differential of two inches w. g. may not cause a considerable volume of air to pass through the material, so that the permeability measured in accordance with the above definition would be zero. If such is the case, the resistance to gas flow of the gas-permeable material should be such that with an air flow of 4 C. F. M./sq. ft. through the uncovered medium, i. e., free of the material to be conveyed, a pressure differential of at least three inches of water across the gas-permeable material is produced.

The apparatus shown in Figs. 5 through 7 includes a truck trailer 32 having side walls 33 and

33', end walls 34 and 34', a roof 35 and a bottom wall 36 defining an enclosed storage space 37. A conveyor pipe 38 extends substantially vertically within the storage space 37, and has its upper end projecting into one of a number of longitudinally-spaced access ports 39 which are provided for loading of material into the storage space. The conveyor pipe 38 is supported from the upper wall 35 of the bin by a split ring clamping means generally indicated at 40. The clamping means is similar to that shown in Fig. 4 and need not be further described here.

A curtain pipe 41 surrounds and has its inner wall spaced from the conveyor pipe 38 by a spacer 42. The upper end of the curtain pipe is adjustably supported from the roof 35 of the storage space by means generally indicated at 43, which is similar to that shown in Fig. 4 and, therefore, not further described.

The adjustable supporting means for both the conveyor pipe and the curtain pipe allow them to be adjusted vertically to suitable positions above the bottom wall 36, the positions being determined by the material being conveyed.

Four longitudinally-extending gas-permeable members 44 and 44' and 45 and 45' are mounted in the bottom wall of the truck. The gas-permeable members 44 and 44' extend between end wall 34 and points substantially midway between the end walls 34 and 34'. The gas-permeable members 45 and 45' extend from end wall 34' to points which also are substantially midway between the end walls 34 and 34'. The gas-permeable members 44 and 44' and 45 and 45' are preferably all inclined with respect to the horizontal at an angle at least equal to the angle of repose of the material in its aerated state, and have their upper ends placed against the end walls 34 and 34', respectively. Plenum chambers 46 and 46' and 47 and 47' extend along and below the gas-permeable members 44 and 44' and 45 and 45', respectively. Gas under pressure is furnished to the plenum chambers through gas-pumping means indicated generally at 48 and 49, which may be a single apparatus and may be carried on the trailer or retained at discharge locations for attachment to the plenum chambers when the trailer reaches such locations.

The lower ends of the gas-permeable members 44 and 45 discharge onto the upper end of a transversely-extending, gas-permeable member 50, and the lower ends of the gas-permeable members 44' and 45' discharge onto a transversely-extending, gas-permeable member 50', aligned with the gas-permeable member 50. The gas-permeable members 50 and 50' are preferably inclined downwardly towards the center of the truck at an angle at least equal to the angle of repose of the material in its aerated state and have their ends terminating below and adjacent the open lower end of the conveyor pipe 38. Plenum chambers 51 and 51' extend along and beneath the gas-permeable members 50 and 50', respectively. The lower ends of plenum chambers 46 and 47 communicate with the upper end of plenum chamber 51, and the lower ends of plenum chambers 46' and 47' communicate with plenum chamber 51', so that gas under pressure from plenum chambers 46 and 47 and 46' and 47' enters plenum chambers 51 and 51', respectively.

A discharge plug, generally indicated at 52, is located directly beneath the conveyor pipe 38 and bridges the gap between the lower ends of the gas-permeable members 50 and 50'. The plug

52 has upper surfaces 53 and 53' which mate with gas-permeable members 50 and 50', respectively, and which form in cross-section, a flattened V. The plug 52 is provided to permit discharge of material through the lower end of the bin, if such discharge should become desirable for any reason.

The truck has a plurality of flow-directing surfaces for directing material in the storage space 37 onto the upper or material-conveying surfaces of the gas-permeable members 44 and 44' and 45 and 45'. These flow-directing surfaces comprise members 54 and 54' extending from side walls 33 and 33', respectively, downwardly to the adjacent sides of the adjacent gas-permeable members, and surfaces 55 and 55' which form an inverted V in cross-section and have their lower ends connected to the adjacent sides of the gas-permeable members. The flow-directing surfaces are all inclined with respect to the horizontal at angles large enough so that the material flows along them onto the gas-permeable members by gravity.

A filter unit 56 is carried in a compartment 57 mounted on end wall 34' of the truck. This compartment has an air-intake opening 58 at its outer side and discharges air after its passage through the filter unit through the end wall 34' into the storage space 37. The filter unit 56 has the same function as the filter units 22 and 22' described in conjunction with the apparatus of Figs. 1 through 4 and, therefore, is not further described here.

A conduit 59 may be connected to the upper end of the conveyor pipe 38 to apply suction to the conveyor pipe, and to conduct air and material from the conveyor pipe to a remotely-located storage bin or the like.

In operation of the apparatus described in connection with Figs. 5 through 7, gas under pressure is forced into the plenum chambers 46 and 46' and 47 and 47' and 51 and 51', through means 48 and 49. The gas flows through the gas-permeable members 44 and 44', 45 and 45' and 50 and 50', into the overlying material on the upper or material-conveying surfaces of the gas-permeable members, thus aerating the material. The aerated material flows downward by the action of gravity from the ends of the bin along the upper surfaces of gas-permeable members 44 and 44' and 45 and 45', until it is discharged onto the gas-permeable members 50 and 50', at which time it flows laterally of the bin downwardly along the upper surfaces of the gas-permeable members 50 and 50', onto the upper surfaces 53 and 53' of the discharge plug 52. Air then passes through the opening 58 in the compartment 57 and the filter unit 56 in such compartment into the material storage space 37. Since the opening 58 is located at a substantial distance from the curtain pipe 41, the air passes over most of the upper surface of the material before reaching the curtain pipe, thus sweeping any dust along with it, so that the danger of dust explosions is materially reduced. After sweeping over the upper surface of the material, the air passes up over the upper end of the curtain pipe 41 and into the passage between the curtain pipe and the conveyor pipe 38. The air stream then flows downwardly in that passage and over the material positioned directly below the conveyor pipe. The air velocity is sufficient that the air entrains the aerated material below the conveyor pipe. After the air entrains the aerated material it reverses its direction and passes upwardly through the conveyor pipe out

of the bin into the transporting means 59. Thus the material within the bin is discharged and conveyed to the proper remote location.

Although the use of air from the surrounding atmosphere as the medium for entraining and carrying the pulverulent material out of the bin has been referred to exclusively above, since atmospheric air is the most convenient and economical gas for the purpose, it is obvious that heated or refrigerated air or other gases, such as those chemically reactive with the material, could be utilized if the results achieved from their use were desired. Accordingly, the invention is not to be considered as limited to the use of air but encompasses the use of such other gases. When the word "air" is used in the appended claims, it is to be understood that such other gases could be substituted therefor.

Though the apparatus and method of the present invention have been described in conjunction with vehicles, such as railway cars and truck trailers, it is obvious that the apparatus is capable of application to any material-storage bin for pulverulent material. Accordingly, the invention is not to be considered restricted to use with vehicles or other mobile bins. Moreover, many other modifications could be made in the apparatus described, without departing from the scope of the invention. Consequently, the invention is not to be considered limited to the apparatus and method specifically shown and described, but rather is limited only by the scope of the appended claims.

I claim:

1. Apparatus for storing and discharging substantially dry pulverulent material comprising a substantially closed bin, at least one upwardly-extending conveyor pipe in the bin having its lower intake end adjacent but spaced above the bottom of the bin, a curtain pipe enclosing and spaced from the conveyor pipe and having its lower end adjacent the lower end of the conveyor pipe, said curtain pipe communicating with the space in the upper part of the bin for receiving air therefrom, means for introducing air into the upper portion of the space in the bin at a point remote from the intake to the curtain pipe to flow across the upper surface of pulverulent material in the bin for introduction into the curtain pipe, means including at least one gas-permeable member in the bottom of the bin for delivering pulverulent material in the bin in an aerated state to a location beneath the conveyor pipe, said gas-permeable member having an upper material-conveying surface forming at least a portion of the lower wall of the bin and being inclined with respect to the horizontal, said gas-permeable member having its lowermost end positioned adjacent the lower intake end of the conveyor pipe, a plenum chamber extending along and beneath the gas-permeable member, and means for introducing a gas into the plenum chamber to pass through the gas-permeable member into material on the material-conveying surface thereof to aerate such material, whereby material on the material-conveying surface of the gas-permeable member flows therealong in an aerated state to a position beneath the lower intake end of the conveyor pipe to be entrained by a stream of air discharged from the lower end of the curtain pipe and to be carried by the air stream upwardly through the conveyor pipe out of the bin.

2. Apparatus for storing and discharging substantially dry pulverulent material comprising a bin, at least one upwardly-extending conveyor pipe in the bin having its lower intake end adjacent but spaced above the bottom of the bin, a curtain pipe enclosing and spaced from the conveyor pipe and having its lower end adjacent the lower end of the conveyor pipe, said curtain pipe being adapted to supply air to the lower end of the conveyor pipe for the entrainment of pulverulent material to be discharged through the conveyor pipe, and means for delivering material in an aerated state to the lower end of the discharge pipe, said means including at least two gas-permeable members in the bottom of the bin and extending in the same general direction, said gas-permeable members being inclined with respect to the horizontal and having their lower ends at opposite sides of and spaced from the lower end of said conveyor pipes, other gas-permeable members in the bottom of the bin extending transversely to said first gas-permeable members and positioned to receive aerated pulverulent material from said first gas-permeable members, said other gas-permeable members being inclined with respect to the horizontal and having their lowermost ends positioned adjacent the lower intake end of the conveyor pipe, each of said gas-permeable members having an upper material-conveying surface forming at least a portion of the lower wall of the bin, a plenum chamber extending along and beneath each of said gas-permeable members and means for introducing a gas into each plenum chamber to pass through the overlying gas-permeable member into material on the material-conveying surface thereof to aerate such material, whereby material on the material-conveying surface of the gas-permeable members flows therealong in an aerated state to a position beneath the lower intake end of the conveyor pipe to be entrained by a stream of air discharged from the lower end of the curtain pipe and to be carried by the air stream upwardly through the conveyor pipe out of the bin.

3. Apparatus for storing and discharging substantially dry pulverulent material as set forth in claim 2 in which the bin is substantially closed, the curtain pipe communicates with the space in the upper part of the bin for receiving air therefrom, and means are provided for introducing air into the upper portion of the space in the bin at a point remote from the intake end of the curtain pipe to flow across the upper surface of pulverulent material in the bin for introduction into the curtain pipe, whereby air so flowing across the upper surface of the pulverulent material will entrain dust particles.
